UNITED STATES PATENT OFFICE.

CHARLES F. BUSH, OF PHILADELPHIA, PENNSYLVANIA.

FLYING MACHINE.

Application filed October 25, 1921. Serial No. 510,326.

To all whom it may concern:

Be it known that I, CHARLES F. BUSH, a citizen of the United States, residing at Philadelphia, in the county of Philadelphia and State of Pennsylvania, have invented 5 certain new and useful Improvements in Flying Machines, of which the following is a specification.

One object of my invention is to provide 10 means which will enable a flying machine, such as an aeroplane, to land more easily and safely; my improved means being so operative that the flying machine can be retarded so that instead of abruptly striking 15 the ground and then jumping or quickly skipping over the surface of the ground as usually occurs, it will be under the control of the operator when landing so that the landing can be effected easily and safely at 20 all times.

Another object is to so construct my improved apparatus that when flying it can be used for elevating, descending and stabilizing purposes in addition to the action 25 of the other parts of the machine.

A further object is to make my improved apparatus of a strong and durable construction and so that it can be easily actuated.

Another object is to so construct my improved apparatus that it will allow a flying machine to land in a smaller space than heretofore possible.

These objects, and other advantageous ends which will be described hereinafter, 35 I attain in the following manner, reference being had to the accompanying drawings in which

Figure 1 is a top plan view of a flying machine in the form of an aeroplane having 40 my invention applied thereto,

Figure 2 is a side elevation of the aeroplane shown in Figure 1,

Figure 3 is an enlarged fragmentary section taken on the line 3—3 of Figure 1,

Figure 4 is an enlarged fragmentary section taken on the line 4—4 of Figure 1,

Figure 5 is a section taken on the line 5—5 of Figure 4,

Figure 6 is a section taken on the line 50 6—6 of Figure 3,

Figures 7, 8 and 9 are diagrammatic views showing a valve which I preferably employ in various positions to effect vari-

ous results from the operation of the apparatus,

Figure 10 is a side view of one of the blades of the device; a portion being shown in section,

Figure 11 is a top plan view of one of the blade-retaining sockets,

Figure 12 is a side elevation of one of the blade-retaining sockets;

Figure 13 is a fragmentary section taken on the line 13—13 of Figure 3,

Figure 14 is an elevation of the valve 65 actuating means,

Figure 15 is a side elevation of an aeroplane showing the apparatus in a different position from that shown in Figure 1 to 12 70 inclusive, and

Figures 16 and 17 are side elevations showing modifications of my improved apparatus.

Referring to the drawings and particularly to Figures 1 to 14 inclusive, 20 represents an aeroplane of a type having an enclosed fuselage 21 which may be of any well known type and I have illustrated the same in the form of a biplane having a motor driven propeller 22 in the front. A motor or engine 23 is positioned within the fuselage and includes a transversely driven shaft 24, the opposite ends of which project beyond the sides of the fuselage as shown in Figure 6 and are secured to the hubs 25 of two devices 26 which are made in accordance with my present invention and since each of these devices is similarly constructed I will describe but one of them in detail and it will be understood that the other of said 90 devices has similar parts similarly arranged and operative.

Each of the devices 26 includes a hub 25 as above stated; said hub having cavities 27 formed in its peripheral surface 28; said cavities preferably being made radial and in the present instance I have illustrated three of these cavities spaced apart equal distances. Each of the cavities has a retaining socket 27 secured therein and secured 100 within each of the sockets is a blade 29. Each of the blades 29 includes a plurality of passages 30, 31 and 32 as clearly shown in Figures 5 and 10. These passages are produced by partitions 33 and 34; the partitions adjacent their outer portions curving 105

toward the forward or face surface 35 of the blade and also being curved in cross section as shown in Figures 4 and 6. The passage 30 is preferably open to the atmosphere at 5 the surface 35 throughout approximately its entire length as shown in Figure 5. The passage 31 has its opening 36, which communicates with the atmosphere, at a position a greater distance from the axis of the shaft 24 than the opening into the passage 30. The passage 32 has its opening 37, which communicates with the atmosphere, at a position a greater distance from the axis of the shaft 24 than the opening 36 of the passage 31 so 10 that it will be understood that during the rotation of the devices the openings 37 will travel in circles or annuli greater than those through which the openings 36 or passages 30 travel so that the air pressure within the various passages will vary for a purpose hereinafter rendered obvious.

The sockets 27^a as shown in Figures 5 and 11 have partitions 38 which are spaced apart to receive the lower portions of the partitions 33 and 34 and the spaces 39, 40 and 41 provided by the partitions 38 register with the inner parts of the respective passages 30, 31 and 32. Each of the blades 29 at a position within the confines of its respective 15 socket has openings 42^a, 42^b and 42^c at the side nearest the fuselage 21; said openings communicating respectively with the passages 30, 31 and 32 and with openings 43^a, 43^b and 43^c in the side of the respective 20 socket 27^a. The hub 25 has groups of ports; each of the groups including ports 44^a, 44^b and 44^c which respectively register with the openings 43^a, 43^b and 43^c so that it will be understood that within the confines of its 25 socket each of the blades has its passage 30 in communication with the port 44^a, its passage 31 in communication with the port 44^b and its passage 32 in communication with the port 44^c. The side walls of the partitions 38 opposed to the ports are curved as 30 shown at 45 so that air passing through the passages is deflected toward and through the ports under certain conditions hereinafter described.

Each of the passages 30, 31 and 32 is divided within its width by a division partition 46 so as to prevent any lateral deflection of the air due to the inner curved surfaces of the passages; said partitions 46 serving in a manner rendered more comprehensible by the following description.

Sleeves 47 surround the shaft 40 and have plate valves 48 thereon which closely fit adjacent the side surfaces 49 of the hubs 25 as 40 clearly shown in Figure 6. Each of these plate valves has a slot 50 extending therethrough; the slot 50 also extending for a predetermined number of degrees, as shown in Figures 7, 8, 9 and 14, around the axis of the shaft 24. This sleeve 47 is mounted in a

bearing 51 in the fuselage 21 and the valve plate 28 can be rotated independently of the rotation of the shaft 24 by the following mechanism.

The sleeve 47 has a gear wheel 52 thereon 70 and an actuating member 53 has a toothed rack 54 as shown in Figure 14 and this member 53 can be moved lengthwise either by hand or by power mechanism so as to effect the rotation of the sleeve and the consequent 75 rotation of the valve 48 so as to move the slot 50 into various positions, for example into the positions as shown in Figures 7, 8 and 9. The outer side surfaces of the fuselage are preferably recessed as shown at 55 80 so that irrespective of what position the slot 50 is in, the slot will always be opposite a portion of the recess 55 on each side of the machine. The arrangement of the parts is such in each of the devices that a portion of 85 the valve plate 48 is capable of closing a number of the ports in each of the groups or series and the port-closing area indicated at 56 extends between the end walls 57 and 58 of the slot 50. The movement of this portion 56 is an important feature of my invention since, for example, when it is moved into the position shown in Figure 7 and allowed to remain there during the rotation of 90 the blades by the shaft 24 it will effect a 95 lifting movement of the flying machine, when it is moved into the position shown in Figure 8 it will effect a forward or normal movement of the machine and when moved into the position shown in Figure 9 it will 100 effect a lowering movement of the machine. It can also be moved into positions intermediate the positions illustrated for effecting other movements of the machine. The resulting action between the slot 50 and the 105 portion 56 will be described in detail hereinafter.

During the rotation of the blades in paths parallel to the opposite sides of the fuselage the various openings of the passages will 110 scoop up or take in air and the air within the passages will be of various pressures for reasons previously stated owing to the relative distance of the openings of the passages with respect to the axis of rotation. This air will be forced through the passages and as the ports of the passages move into registry with the slot 50 the air can escape through the slot, the passages successively 115 discharging the air which has been compressed therein and which cannot escape when the ports are passing the portion 56 of the valve plate. It will be understood therefore that when the ports of each of the blades are passing the portion 56 that they 120 cannot discharge the air which they take in but on the contrary the air is pocketed and offers a resistance against movement of the blade through that portion of the arc of the circle through which they rotate. Thus a 125 130

variable resistance will be set up so that if the portion 56, for example, is moved into the position shown in Figure 7 where it will close the ports of each of the blades as it passes with its surface 35 downward, a resulting lift will be established and the apparatus will operate to effect the lifting movement of the machine. If, for example, the portion 56 is moved into the position shown in Figure 9 then said portion will close the ports when each of the blades is moving with its surface 35 in an upward direction and consequently a lowering movement of the machine will be effected. If the portion 56 is moved into the position shown in Figure 8, the closure of the ports will be effected when the surface 35 of each of the blades is moving through an arc rearward and in this manner a normal or forward movement of the plane will be effected. Various intermediate positions of the portion 56 will effect deflections of the machine and these actions can be accomplished merely by a simple movement of the valve. It will also be noted that these movements of the machine will be gradually effected since the lowest pressure passage is first cut off or closed by the portion 56, then the intermediate pressure passage such as for example as the passage 31 is closed and finally the pressure passage 32 is closed so that the action is gradual. It will of course be understood that any number of passages can be employed in a blade or if desired only a single passage, according to the work which the device is to perform.

In Figure 15, I have shown an arrangement in which the device is moved in positions at right angles to those shown in Figures 1 to 14 inclusive and when the principle of my invention is applied as shown in Figure 15, the devices can be employed for steering purposes or for the purpose of equalizing the action of the machine. In Figures 1 to 15 inclusive I have illustrated the blades as three in number with the blades approximately radial, while in Figures 16 and 17 I have shown an arrangement where the passages of the blades are made approximately spiral in shape; Figure 16 illustrating a construction in which only two blades are employed.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. Apparatus for use on a flying machine,

including rotatable blades having passages through which air is forced due to the rotation of the blades; and means for pocketing the air in said passages during the travel of the blades through a part of their path of movement; substantially as described.

2. Apparatus for use on a flying machine, including rotatable blades having passages through which air is forced due to the rotation of the blades; means for pocketing the air in said passages during the travel of the blades through a part of their path of movement; and means for varying the position in which the pocketing occurs in the path of movement of said blades; substantially as described.

3. Apparatus for use on a flying machine including rotatable blades provided with passages having an inlet and an outlet, means for pocketing the air in said passages during the travel of the blades and means for closing the outlets during the rotation of the blades.

4. Apparatus for use on a flying machine, including means having rotatable blades, each provided with a plurality of passages having inlet openings spaced at different distances from the axis of rotation, said passages having outlets; and means for successively closing said outlets during the rotation of the blades; substantially as described.

5. Apparatus for use on a flying machine, including means having rotatable blades, each provided with a plurality of passages having inlet openings round at different distances from the axis of rotation, said passages having outlets; and means for successively closing said outlets during the rotation of the blades, said means being movable into various positions with respect to the axis of rotation; substantially as described.

6. Apparatus for use on a flying machine, including rotatable means having blades, said blades having passages providing openings for intercepting the air; and a valve having a slot and a portion adjacent the slot, said slot being adapted to communicate with the passages of the blades as they rotate, said adjacent portion of the valve being adapted to close the outlets of said passages; substantially as described.

7. Apparatus for use on a flying machine, including rotatable means having blades, said blades having passages providing openings for intercepting the air; and a valve having a slot and a portion adjacent the slot, said slot being adapted to communicate with the passages of the blades as they rotate, said adjacent portion of the valve being adapted to close the outlets of said passages, said valve being movable, independently of the rotation of the blades, into

various positions relative to the axis of rotation of said blades; substantially as described.

8. Apparatus for use on a flying machine, including a rotatable hub; blades extending therefrom and providing passages having air inlet openings and air outlet ports; and a valve having a slot and a cut-off portion adjacent the slot, said valve being movable independently of the rotation of said hub so as to move said cut-off portion in a position to close said ports as they pass thereby during the rotation of the hub and blades; substantially as described.
9. Apparatus for use on a flying machine, including a rotatable shaft; a hub rotatable in conjunction with said shaft; blades rotatably connected to said hub and having passages provided with air inlet openings, said hub providing ports in communication with said passages; a sleeve; a plate valve connected to the sleeve and having a slot therein; and means for moving said sleeve to move said portions adjacent said slot into various positions, said blade having a portion adapted to form a closure for said ports during the rotation of the blades, said

ports also being adapted to move during their rotation into registry with said slot; substantially as described.

10. Apparatus for use on a flying machine including rotatable blades provided with passages having an inlet and an outlet, means for pocketing the air in said passages during the travel of the blades and means for intercepting the movement of air through the passages during the rotation of the blades.

11. Apparatus for use on a flying machine including rotatable blades provided with passages having an inlet and an outlet, means for pocketing the air in said passages during the travel of the blades and means for successively intercepting the movement of air through the passages during the rotation of the blades.

In testimony whereof I have signed my name to this specification in the presence of two subscribing witnesses.

CHARLES F. BUSH.
